Primary Examiner — Derrick Holland*(74) Attorney, Agent, or Firm* — Boyle Frederickson, S.C.(57) **CLAIM**

The ornamental design for an electronic component, as shown and described.

DESCRIPTION

FIG. 1 is a front elevation view of the electronic component;
FIG. 2 is a (rear) side perspective view thereof;
FIG. 3 is a (front) side perspective view thereof;
FIG. 4 is a bottom plan view thereof;
FIG. 5 is a side elevation view thereof (the opposite side being a mirror image);
FIG. 6 is a rear elevation view thereof; and,
FIG. 7 is a top plan view thereof.
The broken lines shown represent unclaimed subject matter and form no part of the claimed design.
